UNITED STATES PATENT OFFICE.

SAMUEL T. BLEYER, OF CHICAGO, ILLINOIS, ASSIGNOR TO THE HAWLEY DOWN DRAFT FURNACE COMPANY, OF CHICAGO, ILLINOIS, A CORPORATION OF ILLINOIS.

FURNACE.

No. 839,263.

Specification of Letters Patent.

Patented Dec. 25, 1906.

Application filed July 12, 1904. Serial No. 216,241.

To all whom it may concern:

Be it known that I, SAMUEL T. BLEYER, a citizen of the United States, residing at Chicago, in the county of Cook and State of Illinois, have invented certain new and useful Improvements in Furnaces, of which the following is a specification.

My invention relates to boiler-furnaces of the downdraft type, such as the well-known Hawley downdraft-furnace; and the object thereof is to provide means for preventing injury to and deterioration of the side walls of the furnace-chamber and to incidentally increase the heating-surface.

In the usual and well-known downdraft furnaces, particularly of the Hawley type referred to, the side walls of the furnace-chamber are composed of fire-brick or the like, which is exposed directly to the fire and body 10 of the fuel, with the result that the brick is in time burned out and that, moreover, in respect to those side walls adjacent and above the usual water-grate bars clinkers adhere thereto, so that when such clinkers are removed by the fireman the skin or some of the body of the brick adhering to the clinkers will also be removed, besides which the brick is liable to be injured in the use of the fireman's clinker-bar. Consequently in the 20 course of a comparatively short time the bricks have to be renewed, which is of course done at a considerable expense.

According to my present invention I overcome the difficulties mentioned and incidentally obtain increased heating-surface by lining the side walls with water-tubes, which will be exposed directly to the fire and fuel and from which the clinkers may be knocked off or removed with ease and without damage 30 to any part of the furnace.

A second object of my invention is to provide one or more furnaces of the downdraft type with simple and efficient mechanism for constantly feeding coal from a supply-hopper or the like and providing such mechanism with means for feeding either one or 40 more of said furnaces from a single hopper.

Another object of my invention is to so construct and arrange the manifolds and water-tubes and their connections that the same may be assembled at the shop and be ready for instant use at the place of installation, with the result that no steam-fitting or the like is required to be done in the field.

In the drawings, Figure 1 is a sectional elevation of a furnace embodying my improvements, such section being taken through the line 1 of Fig. 2; and Fig. 2, a sectional elevation of such furnace, such section being taken on the line 2 of Fig. 1 and illustrating the furnace in elevation after the boiler-front is removed.

For the purpose of affording a clear and comprehensive understanding of my improvements I have shown my furnace applied to a boiler which in the particular instance is of the Scotch marine type, although it will be understood that a furnace embodying my improvements may be applied to and adapted for use in connection with practically all constructions of boiler. It will therefore be understood that I do not limit myself to the particular application nor to the particular construction of furnace herein illustrated.

The furnace proper (marked 1) is provided in its interior with the two series of upper and lower drums or manifolds 2 and 3, which are respectively connected with the sets of water-tubes 4 and 5, the latter of 50 which constitute a water-grate and in the particular instance herein shown constitute the upper grate. These water-tubes are in the particular instance arranged parallel to each other and have an inclination or pitch 55 downwardly from the rear to the front of the furnace, as clearly indicated in the drawings. The sets of manifolds or drums communicate with each other through the medium of the front and rear boxes 6, there being 60 four of such boxes employed under the construction herein illustrated. These boxes are vertically positioned and arranged adjacent the side walls of the fire or fuel chamber which is formed between the upper and 65 lower sets of water-tubes 4 and 5.

The construction and arrangement of manifolds, water-tubes, and boxes just described are substantially the same as in the ordinary and well-known Hawley downdraft-furnace 70 hereinbefore referred to, with the exception that in the present instance the water-tubes are arranged parallel, the resulting structure being, in effect, a parallelogram, as clearly shown in Fig. 1.

The water-tubes 5 constitute the upper grate, through which the fuel passes, falling upon the lower grate 7, composed, as shown,

75

of ordinary grate-bars, as usual in furnaces of this type; but such fire-grate bars instead of being horizontal, or substantially so, are in the present instance inclined downwardly 5 from back to front, corresponding in inclination to that of the water-grate and the supplemental water-tubes hereinafter referred to.

It will be understood that the fuel is fed, as usual, directly upon the upper fire-grate or 10 water-tubes 5 through a fire-door in the boiler-front or, according to the present construction, from a supply-hopper affording a gravity-feed, as hereinafter explained. In the present construction either method of 15 feeding the fuel may be practiced.

As already suggested, the sides of the furnace-chamber immediately above and adjacent the upper fire-grate have heretofore been made of fire-brick exposed directly to the 20 fuel and fire and liable to become incrusted with clinkers and liable also to become damaged and in time destroyed by the fireman in the removal of the clinkers and incrustations. To overcome this difficulty, which is 25 serious and annoying in practice, I arrange a series of supplemental water-tubes along these side walls, but adjacent the upper or fuel chamber, above the water-tube grate, and the lower or fire chamber, above the fire-grate. Referring first to those supplemental 30 tubes for the fuel-chamber, such tubes (marked 8) are connected with the vertical boxes 6, and thereby form a kind of lining for such walls to protect them against the 35 accumulation of clinkers and the damage consequent upon the removal thereof. These supplemental water-tubes thus communicating with the front and rear vertical boxes 6 and being exposed to the heat of the furnace-chamber above the upper water-grate serve 40 as additional heating-surface. As usual the lower front manifold 3 communicates with uptake-pipes 9, which in turn communicate with the boiler through the horizontal pipes 45 10, such uptake-pipes being located adjacent the side walls of the furnace. As clearly indicated in Fig. 1, however, the lower back manifold 3 is somewhat different than usual in that it is provided toward its ends with 50 depending pipes or legs 11, which are closed at their lower ends. Between the respective depending pipes 11 and the uptakes 9 and against the side walls of the lower or fire chamber are arranged two series of supplemental water-tubes 12, forming the second 55 set thereof, similar in general arrangement, inclination, and function to the supplemental set 8. These tubes 12 are inclined downwardly from back to front the same as the 60 other tubes 8 and the grates, so that said parts are all parallel. The water from the boiler circulates upwardly in the uptake-pipe and passes rearwardly through the two sets of tubes 8 and 12, as well as through the water-grate tubes 5 and the upper set of tubes 4.

The lowermost ones of the set of tubes 12 being connected with the depending legs or extensions 11 near their lower ends, the water in such legs is always in active circulation, so that practically no sediment can accumulate; 70 but, if desired, blow-offs 13 of suitable construction may be provided in such lower ends. By the provision of these supplemental water-tubes the furnace-chambers are substantially inclosed on all sides by the 75 water-tubes, water-grates, and manifolds, thereby securing the maximum heating-surface. Again, according to the present construction it is possible to assemble the manifolds, water-tubes, and boxes in one complete structure or unit at the factory or shop and to ship it in that condition to the place of use or installation, so that only the masonry or brickwork needs to be done after the metal structure has been erected. 80

In the present instance I have illustrated novel and efficient means for automatically supplying or feeding the fuel to the furnace. As herein shown, such means comprise a fuel-hopper 14, from which lead downwardly 90 three legs or spouts 15, whose lower ends communicate with the openings 1^a in the top of the furnace and directly upon the upper set of water-tubes 4, between which the coal or other fuel passes and enters the fire and 95 fuel chamber therebelow. As more particularly shown in Fig. 2, the lower end of the hopper is provided with a pair of dampers 16, meeting half-way in the opening in such end of the hopper and together arranged to close 100 such opening when in their inward position. These dampers are operatively connected at their outer ends with similar bell-cranks 17, pivoted in suitable manner upon opposite sides of the hopper. In addition to this control of the hopper each spout 15 thereof has 105 its own independently arranged and operating damper or valve 18, arranged to be slid inwardly to close the opening at the end of the spouts by means of bell-cranks 19, from 110 whose outer ends depend pull-rods 20, affording the fireman means for readily manipulating such dampers. It is obvious that any one or all of the spouts may be closed by operating the particular damper or dampers 115 and also that the supply of fuel to all of the spouts may be simultaneously cut off by operating the main damper 16. The supply-hopper with its plurality of spouts may operate in connection with a single furnace having a wide fuel-chamber or in connection with several individual furnaces. The hopper and spouts are made so as to be readily removable in order to permit the front of the 120 boiler to be taken off and access had to the 125 interior thereof for the purpose of cleaning the tubes, &c.

I claim—

1. In a downdraft-furnace, the combination of front and rear manifolds in pairs 2 2 130

and 3 3, connecting pipes or boxes 6 6, uptake-pipes 9 and 11, upper and lower sets of water-tubes communicating with such manifolds and forming a fire and fuel chamber between them, the lower set thereof constituting a water-grate, and supplemental sets of water-tubes arranged along the side walls of said chamber and communicating with said boxes 6 6 and pipes 9 and 11.

2. In a downdraft-furnace, the combination of front and rear manifolds arranged in the furnace-chamber, a set of water-tubes forming a grate communicating between the manifolds and dividing the chamber into an upper or fuel chamber and a lower or fire chamber, uptake-pipes communicating with the front manifold, pipes or legs depending from the rear manifold, and a set of supplemental water-tubes communicating between such uptake-pipes and the depending pipes.

3. In a downdraft-furnace, the combination of front and rear manifolds arranged in the furnace-chamber, a set of water-tubes forming a grate communicating between the manifolds and dividing the chamber into an

upper or fuel chamber and a lower or fire chamber, uptake-pipes arranged to communicate between a boiler and the front manifold, pipes or legs closed at their lower ends and depending from the rear manifold near its ends, and supplemental water-tubes communicating at their ends with the uptake-pipes and depending pipes respectively.

4. In a downdraft-furnace, the combination of the upper and lower pairs of manifolds 2 and 3, boxes or pipes 6 connecting such manifolds, upper and lower water-tubes 4 and 5 connecting the members of the pairs of manifolds, uptake-pipes 9 communicating with the front lower manifold, pipes 11 depending from the lower rear manifold, and two sets of supplemental water-tubes arranged along the side wall of the furnace and communicating respectively between the boxes 6 and between the uptake-pipes and depending pipes.

SAMUEL T. BLEYER.
